1,3-METHANO-1H-CYCLOPROPA(cd)
NAPHTHALENE-4,7-DIONES

Hsing Yun Fan, Modesto, Calif., assignor to Shell Oil Company, New York, N.Y., a corporation of Delaware
No Drawing. Filed Jan. 17, 1964, Ser. No. 338,304
9 Claims. (Cl. 260—586)

This application is a continuation-in-part of copending application Serial No. 828,733, filed July 22, 1959, now abandoned.

This invention is concerned with and takes as its principal object the provision of a novel class of polyhydro-methanocyclopropanaphthalenediones, characterized by the following ring structure:

R' being hereinafter defined, and the method of making these novel compounds.

The present invention also concerns and takes as an object compositions containing these compounds and their use as biocides, particularly against nematodes, fungi, bacteria and deleterious microorganisms.

The present invention is particularly concerned with 3a - substituted 1a,2,3,3a - tetrahydro - 1,3 - methano-1H-cyclopropa-(cd)naphthalene-4,7-diones having the following structural formula:

wherein each R, independently, represents hydrogen, middle halogen, unsubstituted alkyl of from one to ten carbon atoms or alkoxy of from one to ten carbon atoms, the alkyl moiety thereof being unsubstituted, R' represents unsubstituted or mono- or poly-(middle halogen)-substituted alkyl of from one to ten carbon atoms, allyl, benzyl, methoxyethyl, hydroxyethyl, dihydroxypropyl, tetrahydrofurfuryl, tetrahydropyranyl and 2,2-dimethyl-1,3-dioxolan-4-ylmethyl. The alkyl groups represented by R, R' and the alkoxy groups represented by R can each be of straight-chain configuration, or of branched-chain configuration.

Of these compounds, the subclass wherein there is an olefinic double bond between the carbon atoms in the 5- and 6-positions and at least two of the R's are middle halogen is of particular interest because of their high toxicity towards microorganisms and nematodes. From the available data, it appears that the 5,6-di-(middle halo) and the 2,5,6 tri(middle halo) compounds of this subclass have the highest toxicity towards a broad spectrum of organisms.

Examples of specific compounds encompassed by the present invention follow.

2,5,6-trichloro-1a,2,3,3a-tetrahydro-3a-ethoxy 1,3-methano-1H-cyclopropa(cd)naphthalene-4,7-dione
2,5(or 6)-dichloro-1a,2,3,3a-tetrahydro-3a,6(or 5)-diethoxy-1,3-methano-1H-cyclopropa(cd)-naphthalene-4,7-dione

2

- 2,5,6-trichloro-1a,2,3,3a-tetrahydro-3a-methoxy-1,3-methano-1H-cyclopropa(cd)naphthalene-4,7-dione
2,5,6-trichloro-1a,2,3-3a-tetrahydro-3a-propoxy-1,3-methano-1H-cyclopropa(cd)naphthalene-4,7-dione
5 2,5,6-trichloro-1a,2,3,3a-tetrahydro-3a-isopropoxy-1,3-methano-1H-cyclopropa(cd)naphthalene-4,7-dione
2,5,6-trichloro-1a,2,3,3a-tetrahydro-3a-hexyloxy 1,3-methano-1H-cyclopropa(cd)naphthalene-4,7-dione
2,5,6-trichloro-1a,2,3,3a-tetrahydro-3a-butoxy-1,3-methano-1H-cyclopropa(cd)naphthalene-4,7-dione
2,5,6-trichloro-1a,2,3,3a-tetrahydro-3a-pentyloxy-1,3-methano-1H-cyclopropa(cd)naphthalene-4,7-dione
15 2,5,6-trichloro-1a,2,3,3a-tetrahydro-3a-octyloxy-1,3-methano-1H-cyclopropa(cd)naphthalene-4,7-dione
2,5,6-trichloro-1a,2,3,3a-tetrahydro-3a-nonyloxy-1,3-methano-1H-cyclopropa(cd)naphthalene-4,7-dione
2,5,6-trichloro-1a,2,3,3a-tetrahydro-3a-dodecyloxy-1,3-methano-1H-cyclopropa(cd)naphthalene-4,7-dione
20 2,5,6-trichloro-1a,2,3,3a-tetrahydro-3a-(2-hydroxyethoxy)-1,3-methano-1H-cyclopropa(cd)-naphthalene-4,7-dione
2,5,6-trichloro-1a,2,3,3a-tetrahydro-3a-(2,3-dihydroxypropoxy)-1,3-methano-1H-cyclopropa(cd)naphthalene-4,7-dione
25 2,5,6-trichloro-1a,2,3,3a-tetrahydro-3a-(dibromoethoxy)-1,3-methano-1H-cyclopropa(cd)naphthalene-4,7-dione
30 2,5,6-trichloro-1a,2,3,3a-tetrahydro-3a-(dichloroethoxy)-1,3-methano-1H-cyclopropa(cd)naphthalene-4,7-dione
2,5,6-trichloro-1a,2,3,3a-tetrahydro-3a-(1,2-dibromopropoxy)-1,3-methano-1H-cyclopropa(cd)-naphthalene-4,7-dione
35 2,5,6-trichloro-1a,2,3,3a-tetrahydro-3a-(1,2-dibromopropoxy)-1,3-methano-1H-cyclopropa(cd)-naphthalene-4,7-dione
2,5,6-trichloro-1a,2,3,3a-tetrahydro-3a-(tetrahydrofuryloxy)-1,3-methano-1H-cyclopropa(cd)-naphthalene-4,7-dione
40 2,5,6-trichloro-1a,2,3,3a-tetrahydro-3a-(tetrahydropyran-2-ylmethoxy)-1,3-methano-1H-cyclopropa(cd)naphthalene-4,7-dione
2,5,6-trichloro-1a,2,3,3a-tetrahydro-3a-(2,2-dimethyl-1,3-dioxolan-4-ylmethoxy)-1,3-methano-1H-cyclopropa(cd)naphthalene-4,7-dione
45 The novel compounds of the present invention may be made by alcoholysis of halogen-substituted polyhydro-1,4-methanonaphthalene-5,8-diones having halogen substituted on at least one of the carbon atoms of the 1,4-ethano bridge (that is, on at least one of the carbon atoms in the 2- and 3-positions) and having a double bond, actual or potential (by virtue of readily removable substituent groups or atoms), in the homoallylic (4a, 8a) position. The most valuable compounds of the invention have been prepared from such halogen-substituted polyhydro-1,4-methanonaphthalene-5,8-diones that are substituted by chlorine at least in both the 2- and 3- or both the 2- and 9-positions of the nucleus. Particularly valuable as starting materials are the tetrahydro- and the hexahydro-1,4-methanonaphthalene - 5,8 - diones that are thus substituted by chlorine.
50 Of particular interest as starting materials are the 2,6,7,9 - tetrahalo - 1,2,3,4 - tetrahydro - 1,4 - methanonaphthalene-5,8-diones such as 2,6,7,9-tetrachloro-1,2,3,4-tetrahydro - 1,4 - methanonaphthalene - 5,8 - dione and 2,4a,6,7,8a,9 - hexahalo - 1,2,3,4,4a,8a - hexahydro - 1,4 - methanonaphthalene-5,8-diones such as 2,4a,6,7,8a,9-hexachloro - 1,2,3,4,4a,8a - hexahydro - 1,4 - methanonaphthalene-5,8-dione.
55 60 The alcoholysis of these halogen-substituted polyhydro-1,4-methanonaphthalene-5,8-diones leads to the removal of a halogen atom from the 1,4-ethano bridge, to forma-

tion by homoallylic displacement of a cyclopropane ring that includes one of the ring carbon atoms to which the methano bridge is bonded, and to introduction of the group $R'O-$ (R' being as defined hereinbefore) onto one of the two carbon atoms that are common to the fused bicycloheptane (or -ene) and hexatomic quinoid rings of the parent halogen-substituted polyhydro-1,4-methanonaphthalene-5,8-dione. For accomplishing the alcoholsysis there may be employed an alcohol $R'OH$, corresponding to the group $R'O-$ that it is desired to introduce, in conjunction with an alkaline acting or other known alcoholsysis agent, or there may be employed a reagent which serves both as the source of the $R'O-$ group and as the catalyst.

The choice of the alcohol, $R'OH$, will depend upon the substituent group $R'O-$ that will be present in the desired product. Illustrative alcohols which may be used include, among others, methyl alcohol, ethyl alcohol, propyl alcohol, isopropyl alcohol, the butyl alcohols, allyl alcohol, and higher aliphatic alcohols containing up to ten or even more carbon atoms; methoxyethyl alcohol, hydroxyethyl alcohol, dihydroxypropyl alcohol, tetrahydrofurfuryl alcohol, tetrahydropyranyl alcohol and benzyl alcohol.

Alkaline acting materials which may be used as agents for the alcoholsysis include such inorganic alkaline-reacting materials as the oxides, hydroxides, and carbonates of the alkali metals (including ammonium) and of the alkaline earth metals, for example, sodium hydroxide, potassium hydroxide, lithium hydroxide, sodium carbonate, ammonium hydroxide, ammonium carbonate, sodium bicarbonate, calcium oxide, barium hydroxide, and the like. Organic bases, such as amines and amine salts and quarternary ammonium bases, including triethyl amine, ethanolamine, triethanolamine, triethyl amine phosphate, 25 benzyltrimethylammonium hydroxide, and the like, may also be employed. Other known alcoholsysis agents which may be used include, for example, metals that are capable of replacing hydrogen from the hydrohalic acids, e.g., zinc, magnesium, iron, etc., preferably employed in finely divided state, e.g., zinc dust, iron filings, brass spelter, or the like. Zinc has been found to be an especially effective agent, both as the sole agent and used in conjunction with one or more alkaline acting materials as described hereinabove.

Instead of reacting the parent halogen-substituted polyhydro-1,4-methanonaphthalene-5,8-dione with an alcohol in the presence of a separate alcoholsysis agent, the alcoholsysis may also be conducted by treatment of the parent halogen-substituted polyhydro-1,4-methanonaphthalene-5,8-dione with an alkoxide of an alkali metal, of an alkaline earth metal, or of an earth metal, corresponding to the group $R'O-$ that it is desired to introduce, such as sodium ethoxide, potassium methoxide, magnesium ethoxide, aluminum triisopropoxide, aluminum phenoxide, etc.

The alcoholsysis step (that concomitantly leads to formation of the cyclopropane ring, as discussed hereinbefore) of the process of the present invention may be conducted by heating together the parent halogen-substituted polyhydro-1,4-methanonaphthalene-5,8-dione, the alkaline acting material in sufficient quantity to neutralize liberated hydrohalic acid, and the alcohol in at least the stoichiometric amount. Where an alkoxide is used as both the source of the $R'O-$ group and as the alkaline acting material, the amount of the alkoxide will, of course, be determined on the basis of stoichiometry. A convenient method of conducting the reaction is to heat the reactants together at reflux in the presence of a solvent, which may be an inert solvent such as benzene, xylene, toluene, heptane, decane, or other saturated or aromatic hydrocarbon solvent, or may, even more simply, be the alcohol itself present in excess over the amount required for the reaction. Reaction temperatures within the range of from about room temperatures up to about 75

200° C., preferably up to about 140° C., may be employed, although these are not critical and the optimum temperature will depend upon the particular reactants that are involved. After completion of the reaction, the product can be recovered by conventional methods, e.g., from crystallization from solvents, extraction, etc. The products of the invention are, in general, high-melting solids that, owing to the likelihood of decomposition, are not amenable to distillation.

In schematic terms, compounds of this invention can be prepared by the following routes (R and R' have the respective meanings already given and $R_0=R$, the subscript being used for clarity):

A.

B.

C.

D.

By way of example, one complete sequence of steps for the production of compounds of the present invention follows. It should be understood that though the following sequence of steps shows the preparation of 2,5,6 - trichloro - 1a,2,3,3a - tetrahydro - 3a - ethoxy - 1,3-methano-1H-cyclopropa(cd)naphthalene - 4,7 - dione it also applies to other compounds of the present invention which differ only in the substituents on the ring.

An alternative method for the production of this compound follows:

Another preparation of 2,5,6 - trichloro - 1a,2,3,3a - hexahydro - 3a - ethoxy - 1,3 - methano - 1H - cyclopropa (cd) naphthalene - 4,7-dione from 1,4 - dihydro - 1,4 - methanonaphthalene - 5,8 - diol follows:

Another method for the preparation of compounds of the present invention employing the cyclopentadiene-chloranil adduct follows:

Employing the diol diacetate so produced, 2,5,6-trichloro-1a,2,3,3a-tetrahydro - 3a - ethoxy - 1,3 - methano - 1H - cyclopropa(cd)naphthalene - 4,7 - dione may be made in accordance with methods already described. Other compounds of the present invention may also be made in accordance with the described method employing the cyclopentadienechloranil adduct.

Another preparation of compounds of the present invention as exemplified by 2,5,6 - trichloro - 1a,2,3,3a - tetrahydro - 3a - ethoxy - 1,3 - methano - 1H - cyclopropa (cd) naphthalene - 4,7 - dione follows. In this instance, the product is a stereoisomer of the compound prepared in accordance with methods already described. Those versed in the art will recognize that four isomers of this dione are possible.

The 1,4-methano - 1H - cyclopropa(cd)naphthalene - 5,8 - dione obtained by synthesis from the cyclopentadiene-chloranil adduct is a stereoisomer of the product obtained by synthesis from the cyclopentadiene - p - benzoquinone adduct. The principle upon which the difference between these compounds is based can be gleaned from a consideration of the basic nortricyclene structure present in the compounds of this invention. This discussion ignores isomer pairs which are possible by virtue of one being the mirror image of the other; these are the well-known dl pairs of optical isomers.

In nortricyclene a system exists which contains a cyclopropane ring each of whose carbon atoms is connected to a common carbon atom through a methylene bridge. This arrangement of seven carbon atoms provides a system having a three-fold axis of symmetry which is to be seen in its three planes of symmetry each defined by the common carbon atom, one methylene carbon and the carbon atom of the cyclopropane ring to which the latter is joined. By virtue of this symmetry all three methylene carbons are geometrically equivalent and the external bonds of a methylene group are likewise equivalent. A consequence of these relationships is that a nortricyclene having one of its methylene carbons with a single substituent or even two different substituents exists in but one geometric form. It will be immediately recognized that when this system bears two substituents on different methylene carbons a number of different geometric forms can exist.

The novel 1,3 - methano-1H - cyclopropa(cd)naphthalene-5,8-diones of this invention have a cyclohexenedione unit fused with a nortricyclene unit as shown in the following illustrations for IV.

It can be seen in this system that carbon atom 3a when considered as part of the nortricyclene unit has one of its external bonds as part of the cyclohexenedione ring structure. Since the enedione portion of the molecule is symmetrical and the bond between carbon atoms 7a and 7

is the only possible external bond for the nortricyclene unit at that point, no new elements of geometry are introduced by these structural units. Thus, on the basis of the reasoning presented above for nortricyclene, only one geometric form is possible for 1a,2,3,3a-tetrahydro-1,3-methano-1H-cyclopropanaphthalene-4,7-dione IV, as well as for the case where position 3a of IV is substituted, as by ethoxyl.

When, however, the structure represented by IV bears in addition to an ethoxyl group at position 3a a chlorine atom at position 2 or 8, then four geometric forms are evident. These four isomers can be understood when the chlorine atom is positioned at orientation *c*, *d*, *e*, or *f* of IV. Each of these external bonds of carbon atoms 2 and 8 is recognized as being differently oriented when viewed against the two unlike substitutions in the nortricyclene unit at position 3a.

The distinguishing features of these orientations can also be recognized in considering the terminology *cis-trans* and *syn-anti* which can be employed. With bond 3a-4 as a reference point, orientation *c* is *cis* when considering the geometry of the bonding of these two bonds to their common cyclopentane ring, in this case 1a, 2, 3, 3a, 7a. Then taking the plane defined by atoms 3, 3a and 7a as a point of reference, it can be seen that orientation *c* is on the same side of the plane as bond 3a-4. Thus, *c* is completely designated as *cis-syn*. Using these two frames of reference, the designations become for *d*, *trans-syn*; for *e*, *cis-anti*; for *f*, *trans-anti*.

These symbolisms become especially valuable in differentiating by name the four isomers, say of 2,5,6-trichloro-1a,2,3,3a-tetrahydro-3a-ethoxy-1,3-methano-1H-cyclopropanaphthalene. It is recognized that in this composition the chlorine atoms at positions 5 and 6 are symmetrically placed and thus do not produce new geometric forms. Thus, the chlorine at position 2 can be assigned any one of the four spatial orientations mentioned above. Although in the perspective drawing of IV positions 2 and 8 appear unlike, the difference no longer exists in a non-perspective representation of the molecule, the two methylene groups of IV appearing equivalent as they do in nortricyclene. Since the naming of compounds following the practice of Chemical Abstracts requires the assigning of the lowest number to a substituent and only non-perspective representations are considered, position 2 is used for the third chlorine. Then, with the four symbolisms a complete name can be given to any one of the isomers.

It is believed that the principal product of the method, starting with the cyclopentadiene (p-benzoquinone) adduct, can be represented non-perspectively by having its chlorine in the 2-position oriented *cis-anti* and that where the cyclopentadiene-chloranil adduct is employed the similar chlorine is oriented *trans-syn*. It is also believed that the crude products of the two methods also contain varying amounts of the other isomers involving the orientation of the chlorine at position 2.

The invention can be best illustrated by the following examples which demonstrate the various embodiments.

EXAMPLE I

2,5,6-trichloro-1a,2,3,3a-tetrahydro-3a-ethoxy-1,3-methano-1H-cyclopropanaphthalene-4,7-dione

9.36 grams of 2,6,7,9-tetrachloro-1,2,3,4-tetrahydro-1,4-methanonaphthalene-5,8-dione, 2.52 grams of sodium bicarbonate, 14 milliliters of benzene, and 33 milliliters of absolute ethanol were refluxed with stirring for six hours. The reaction mixture was filtered to remove the inorganic material. The filtrate was evaporated and filtered to give 6.4 grams of 2,5,6-trichloro-1a,2,3,3a-tetrahydro-3a-ethoxy-1,3-methano-1H-cyclopropanaphthalene-4,7-dione, melting point, 172-173° C.

Analysis.—Calculated for $C_{13}H_{11}Cl_3O_3$: Percent Cl, 75

48.6; percent C, 33.0; percent H, 3.4. Found: Percent Cl, 48.6; percent C, 32.6; percent H, 3.6.

In the same manner, 2,5,6-trichloro-1a,2,3,3a-tetrahydro-3a-ethoxy-1,3-methano-1H-cyclopropanaphthalene-4,7-dione, melting point 48-49° C., was prepared substituting for the ethanol an equivalent amount of n-hexyl alcohol.

Analysis.—Calculated for $C_{17}H_{19}Cl_3O_3$: Percent Cl, 28.2; percent C, 54.1; percent H, 5.0. Found: Percent Cl, 28.0; percent C, 54.2; percent H, 5.2.

EXAMPLE II

78 grams of 2,6,7,9-tetrachloro-1,2,3,4-tetrahydro-1,4-methanonaphthalene-5,8-dione was suspended in 960 milliliters of absolute ethanol and 8 grams of zinc dust was added. The mixture was refluxed for three hours, filtered and allowed to stand overnight. The precipitate which formed was removed by filtration and was crystallized from methanol. The product analyzed as 2,5,6-trichloro-1a,2,3,3a-tetrahydro-3a-ethoxy-1,3-methano-1H-cyclopropanaphthalene-4,7-dione, melting point 169-171° C., amount 20 grams.

EXAMPLE III

25 To 9.36 grams purified 2,6,7,9-tetrachloro-1,2,3,4-tetrahydro-1,4-methanonaphthalene-5,8-dione dissolved in 100 milliliters of benzene there was added dropwise a solution of sodium ethoxide in ethanol (0.69 gram of Na in 100 milliliters of ethanol) with stirring in about 40 minutes at 30 room temperature. The reaction mixture was filtered to remove inorganic salt and the filtrate was evaporated to about 50 milliliters chilled and filtered to yield 6.2 grams of light yellow material, melting point, 169-171° C. Analysis showed this material to be 2,5,6-trichloro-35 1a,2,3,3a-tetrahydro-3a-ethoxy-1,3-methano-1H-cyclopropanaphthalene-4,7-dione.

EXAMPLE IV

40 5.5 grams of 2,6,7,9-tetrachloro-1,2,3,4-tetrahydro-1,4-methanonaphthalene-5,8-dione was dissolved in 150 milliliters of boiling absolute ethanol and 3 grams of aluminum ethoxide was added. The mixture was refluxed for 30 minutes, filtered and evaporated to a small volume. Water was added and the product was extracted with benzene. The benzene extract was evaporated to near dryness and the residue was triturated with hexane to give the desired product as a precipitate which weighed one gram, melting point 169-171° C.

EXAMPLE V

45 4.7 grams of 2,6,7,9-tetrachloro-1,2,3,4-tetrahydro-1,4-methanonaphthalene-5,8-dione was refluxed in 25 milliliters of benzene and 25 milliliters of ethanol with one gram of $Mg(OCH_2CH_5)_2$ for 7 hours. The reaction mixture was filtered and the filtrate was evaporated to a small volume, chilled and filtered to give 1.9 grams of 2,5,6-trichloro-1a,2,3,3a-tetrahydro-3a-ethoxy-1,3-methano-1H-cyclopropanaphthalene-4,7-dione, melting point 166-169° C.

EXAMPLE VI

50 60 4.7 grams 2,6,7,9-tetrachloro-1,2,3,4-tetrahydro-1,4-methanonaphthalene-5,8-dione and 0.72 gram of $(NH_4)_2CO_3$

were refluxed in 30 milliliters of benzene and 70 milliliters of absolute ethanol for 20 hours. The reaction mixture was evaporated to a small volume and filtered to give 2.4 grams of 2,5,6-trichloro-1a,2,3,3a-tetrahydro-3a-ethoxy-1,3-methano-1H-cyclopropanaphthalene-4,7-dione, melting point 163-166° C.

EXAMPLE VII

4.7 grams of 2,6,7,9-tetrachloro-1,2,3,4-tetrahydro-1,4-methanonaphthalene-5,8-dione was dissolved in 50 milliliters of benzene and a solution of sodium hydroxide in ethanol (0.6 gram NaOH in 50 milliliters C_2H_5OH) was

11

added in 30 minutes with vigorous stirring. The mixture was allowed to stand for another 30 minutes and filtered to remove the inorganic sodium chloride. The filtrate was evaporated to a small volume, filtered to give 2.75 grams 2,5,6-trichloro-1a,2,3,3a-tetrahydro-3a-ethoxy - 1,3-methano-1H-cyclopropanaphthalene-4,7-dione. 5

EXAMPLE VIII

0.7 grams of 2,6,7,9-tetrachloro-1,2,3,4-tetrahydro-1,4-methanonaphthalene-5,8-dione was dissolved in 50 milliliters of benzene and a solution of 2.23 grams triethanolamine in 50 milliliters of ethanol was added dropwise with vigorous stirring over one hour. The reaction mixture was stirred for another 30 minutes and the amine salt formed during the reaction was filtered. The filtrate was evaporated to a smaller volume and chilled to give 3.6 grams of product which upon washing with water and methanol yielded 2.65 grams of 2,5,6-trichloro-1a,2,3,3a-tetrahydro-3a-ethoxy-1,3-methano - 1H - cyclopropanaphthalene-4,7-dione, melting point 166-169° C. 10

EXAMPLE IX

5.0 grams of 2,4a,6,7,8a,9 - hexachloro - 1,2,3,4,4a,8a-hexahydro-1,4 - methanonaphthalene - 5,8 - dione was refluxed with 2.05 grams of zinc dust in 100 milliliters of absolute ethanol for 3 hours. A gradual change of color to orange and then to brown was apparent. The reaction mixture was filtered to remove zinc. The filtrate was then shaken with water and an amorphous brown solid was separated. The solid which was insoluble in hexane, but very soluble in benzene or methanol, was then extracted with carbon tetrachloride, yielding a dark red solution and an insoluble dark residue, which was discarded. The dark red solution was evaporated to a small volume and cooled, and an amorphous brown solid which separated was discarded. The filtrate was evaporated to dryness and the residue was dissolved in methyl alcohol and cooled. Two-tenths gram of yellow crystals, melting point 148-158° C., was obtained. These crystals were recrystallized from ethyl alcohol, yielding the desired product having a melting point of 164-166° C. 40

EXAMPLE X

38.3 grams of 2,4a,6,7,8a,9-hexachloro-1,2,3,4,4a,8a-hexahydro-1,4-methanonaphthalene-5,8-dione was mixed with 6.3 grams of zinc, 9 grams of sodium bicarbonate, 80 milliliters ethanol and 40 milliliters of benzene. The mixture was then refluxed for 4 hours and the inorganic material was filtered. The filtrate was concentrated to a small volume to give 10 grams of a tan solid having a yellowish tint, melting point 161-167° C., mixed melting point with 2,5,6-trichloro-1a,2,3,3a-tetrahydro-3a-ethoxy-1,3-methano-1H-cyclopropanaphthalene - 4,7 - dione, 163-169° C. This product was recrystallized from benzene to give 8 grams of pure product as a light yellow material, melting point 170-172° C. 45

In the preceding examples, the differences in melting points of the respective products are attributable to differences in purity. Pure 2,5,6-trichloro-1a,2,3,3a-tetrahydro-3a-ethoxy-1,3-methano - 1H - cyclopropanaphthalene-4,7-dione melts at approximately 172-3° C. as illustrated by the preparation described in Example I. 50

EXAMPLE XI

2,5,6-trichloro-1a,2,3,3a-tetrahydro-3a-ethoxy - 1,3 - methano-1H-cyclopropanaphthalene-4,7 - dione (isomer of the compound of Examples I through X)

15.6 grams of the adduct of cyclopentadiene and chloranil was suspended in 50 milliliters of CH_2Cl_2 and a stream of chlorine gas was introduced. No evolution of heat was observed. A few iodine crystals were then added to the mixture. An exothermic reaction was observed. The chlorination was continued until no heat was evolved. The reaction mixture was filtered and the solid was washed with CH_2Cl_2 to give a yellow precip- 55

12

itate which was chloranil, weight 1.2 grams. The filtrate was evaporated to dryness and the residue was treated with hexane and filtered to give a tan precipitate which melted at 147-154° C. and depressed the melting point of the starting material. This material was again chlorinated in 50 milliliters of CH_2Cl_2 in the presence of iodine for half an hour. The reaction mixture was evaporated to dryness and triturated with hexane to give a light tan solid, melting point 161-165° C., weight 12.5 grams. This product was recrystallized from ethyl acetate to give the product as a light yellow solid melting at 170-171° C., weight 7.0 grams (A). Second crop: 4.2 grams, melting point 164-167° C. (B). Crop (A) was analyzed. 10

Analysis.—Calculated for $\text{C}_{11}\text{H}_6\text{Cl}_6\text{O}_2$: % Cl, 55.3; % C, 34.5; % H, 1.6. Found: % Cl, 55.2; % C 34.4; % H 1.6. 15

5.0 grams of the above-described product (4.2 grams of (B) and 0.8 gram of (A)) were mixed with 0.85 gram of zinc and 80 milliliters of absolute ethanol. The mixture was refluxed with stirring for 4½ hours and filtered to remove unreacted zinc. The filtrate was concentrated to yield 1.8 grams of product as a yellow solid, melting point 200-202° C. 20

Analysis.—Calculated for $\text{C}_{11}\text{H}_6\text{Cl}_4\text{O}_2$: % Cl, 45.5; % C, 42.3; % H, 1.9. Found: % Cl, 45.5; % C, 41.8; % H, 2.2. 25

1.3 grams of the above tetrachloroquinone was refluxed with 0.42 gram NaHCO_3 in 40 milliliters of ethanol for 6 hours and the mixture was filtered to remove the inorganic material. The filtrate was evaporated to small volume to give 1.1 grams of light yellow product, melting point 177-179° C. It was recrystallized from ethyl acetate to give a crystalline product, M.P. 180-1° C. 30

Analysis.—Calculated for $\text{C}_{13}\text{H}_{11}\text{Cl}_3\text{O}_3$: % Cl, 33.1. 35

EXAMPLE XII

2,5,6 - Trichloro - 1a,2,3,3a - tetrahydro - 3a-ethoxy-1,3-methano - 1H - cyclopropanaphthalene - 4,7-dione (isomer of the compound of Examples I through X)

Methods of preparation of 2,3,6,7-tetrachloro-1,2,3,4-tetrahydro-1,4-methanonaphthalene-5,8-dione by chlorination of 6,7-dichloro-1,4-dihydro-1,4-methanonaphthalene-5,8-dione. 40

(1) 355 grams of gaseous chlorine was added to a solution of 964 grams of 6,7 - dichloro - 1,4 - dihydro - 1,4-methanonaphthalene-5,8-dione in 4800 milliliters methylene chloride over a period of 1½ hours with constant stirring. The exothermic reaction brought the reaction mixture to boiling. After the addition of chlorine the reaction mixture was evaporated to a smaller volume, chilled, filtered and washed with methanol to give 655 grams of yellow solid, melting point, 230-4° C. It was recrystallized from ethyl acetate to give yellow crystalline 2,3,6,7 - tetrachloro - 1,2,3,4 - tetrahydro - 1,4 - methanonaphthalene-5,8-dione melting at 236.5-7° C. 45

Analysis.—Calculated for $\text{C}_{11}\text{H}_6\text{O}_2\text{Cl}_4$: % C, 42.3; % H, 1.9; % Cl, 45.5. Found: % C, 42.7; % H, 2.0; % Cl, 45.3. 50

60 A suspension of 468 grams of this isomer of 2,3,6,7-tetrachloro - 1,2,3,4-tetrahydro-1,4-methanonaphthalene-5,8-dione and 126 grams of sodium bicarbonate in 4500 milliliters of absolute alcohol was refluxed for 24 hours. The reaction mixture was filtered while hot to remove the 65 inorganic salt which gave a positive test for chloride and negative test for carbonate. The filtrate was evaporated to a smaller volume, chilled, filtered and washed several times with methanol to give 238 grams of a solid melting at 170-172°. Its was recrystallized from ethyl acetate and then from benzene to yield 2,5,6-trichloro-1a,2,3,3a-tetrahydro - 3a - ethoxy - 1,3 - methano - 1H - cyclopropanaphthalene-4,7-dione, as a light yellow crystalline solid, melting point, 174.5-175° C. The identity of the product was confirmed by elemental analysis: 70

Analysis.—Calculated for $\text{C}_{13}\text{H}_{11}\text{O}_3\text{Cl}_3$: % C, 48.5;

% H, 3.4; % Cl, 33.1. Found: % C, 48.3; % H, 3.6; % Cl, 33.2.

EXAMPLE XIII

2,5(or 6)-Dichloro-1a,2,3,3a-tetrahydro-3a,6(or 5)-diethoxy-1,3-methano-1H-cyclopropano(cd)naphthalene-4,7-dione

9.36 grams of 2,6,7,9-tetrachloro-1,2,3,4-tetrahydro-1,4-methanonaphthalene-5,8-dione was dissolved in 200 milliliters of boiling absolute ethanol and a solution of sodium ethoxide, prepared by dissolving 1.38 grams of sodium in 50 milliliters of ethanol, was added dropwise with stirring in about half an hour. A precipitate of sodium chloride which formed immediately was filtered. The filtrate was evaporated to a small volume to give two crops: Crop A, 3.2 grams, melting point 108-118°, and Crop B, 0.7 grams, melting point 108-114°. Crop A was recrystallized from methanol to give 2.6 grams of product, melting point 112-114°, which was analyzed.

Analysis.—Calculated for $C_{15}H_{16}Cl_2O_4$: % Cl, 21.5. Found: % Cl, 21.6.

EXAMPLE XIV

2,5,6-trichloro-1a,2,3,3a-tetrahydro-3a-methoxy-1,3-methano-1H-cyclopropano(cd)naphthalene-4,7-dione

9.3 grams of purified 2,6,7,9-tetrachloro-1,2,3,4-tetrahydro-1,4-methanonaphthalene-5,8-dione was dissolved in 200 milliliters of boiling methanol and a solution of sodium methoxide in methanol was added with stirring in about 20 minutes. The resulting mixture was evaporated and the precipitate was filtered and washed with water and methanol to give 3.1 grams of products, melting point 148-153° C., which was recrystallized from methanol several times to yield 2.7 grams of light yellow product, melting point 158-159° C.

Analysis.—Calculated: % chlorine, 34.6; % methoxyl, 10.1. Found: % chlorine, 33.8; % methoxyl, 9.6.

EXAMPLE XV

2,5,6-trichloro-1a,2,3,3a-tetrahydro-3a-propoxy-1,3-methano-1H-cyclopropano(cd)naphthalene-4,7-dione

9.3 grams of purified 2,6,7,9-tetrachloro-1,2,3,4-tetrahydro-1,4-methanonaphthalene-5,8-dione was dissolved in 100 milliliters of benzene and a solution of sodium propoxide was added dropwise with stirring in one hour. The reaction mixture was filtered to remove 1.55 grams of sodium chloride and the filtrate was concentrated to remove all benzene and chilled to give a gummy precipitate. Addition of methanol to the precipitate yielded a light yellow material, melting point 95-98° C., weight 4.45 grams. This product was recrystallized from methanol, yielding 3.5 grams of crystalline product, melting point 100-101° C.

Analysis.—Calculated for $C_{14}H_{12}Cl_3O_3$: % Cl, 31.8. Found: % Cl, 31.3.

EXAMPLE XVI

2,5,6-trichloro-1a,2,3,3a-tetrahydro-3a-methoxyethoxy-1,3-methano-1H-cyclopropano(cd)naphthalene-4,7-dione

31.2 grams of 2,6,7,9-tetrachloro-1,2,3,4-tetrahydro-1,4-methanonaphthalene-5,8-dione was heated on a steam

bath in 75 milliliters of methyl cellosolve and a solution of 4.8 grams of $(NH_4)CO_3$ in 50 milliliters water was added. The reaction mixture was heated for one-half hour and diluted with water. The gummy precipitate obtained was washed with water and dissolved in boiling methanol. Three crops were obtained. The first crop melted at 175-180° C. and weighed 5.5 grams. The second crop melted at 80-90° C. and weighed 11 grams, and the third crop melted at 105-110° C. and weighed one gram. The residue was discarded. The second crop was recrystallized from methanol to give 6 grams of light yellow material, melting point 91-96° C., which was chromatographed through a column of activated alumina in CH_2Cl_2 to give four grams of light yellow crystalline product, melting point 95.5-96.5° C.

Analysis.—Calculated for $C_{14}H_{13}Cl_3O_4$: % Cl, 30.3; % C, 47.8; % H, 3.7. Found: % Cl, 30.5; % C, 47.5; % H, 3.7.

EXAMPLE XVII

2,5,6-trichloro-1a,2,3,3a-tetrahydro-3a-(chloroethoxy)-1,3-methano-1H-cyclopropano(cd)naphthalene-4,7-dione

31.2 grams of 2,6,7,9-tetrachloro-1,2,3,4-tetrahydro-1,4-methanonaphthalene-5,8-dione and 8.4 grams $NaHCO_3$ were suspended in 50 milliliters benzene and 100 milliliters $ClCH_2CH_2OH$. The mixture was refluxed for 5 hours at 92° C. with stirring. The solvent was stripped to about one-third its original volume and washed with water. The gummy residue was triturated with MeOH and allowed to stand. A solid was formed which was filtered and washed with MeOH to give 14 grams of light yellow material, melting point 134-137° C. This product was recrystallized from benzene to give solid product, melting point 136-137° C.

Analysis.—Calculated for $C_{13}H_{10}O_3Cl_4$: % Cl, 39.9; % C, 43.8; % H, 2.8. Found: % Cl, 40.2; % C, 44.0; % H, 3.0.

EXAMPLE XVIII

2,5,6-trichloro-1a,2,3,3a-tetrahydro-3a-allyloxy-1,3-methano-1H-cyclopropano(cd)naphthalene-4,7-dione

62.4 grams of 2,6,7,9-tetrachloro-1,2,3,4-tetrahydro-1,4-methanonaphthalene-5,8-dione was mixed with 17.6 grams $NaHCO_3$ in 100 milliliters benzene and 50 milliliters of allyl alcohol and then refluxed for 3 hours. The reaction mixture was filtered to remove the inorganic salt and the filtrate was evaporated to dryness and the residue was triturated with MeOH to give a yellow precipitate which was recrystallized from MeOH to give 12 grams of light yellow product, melting point 125-126° C.

Analysis.—Calculated for $C_{14}H_{11}O_3Cl_3$: % Cl, 31.9; % C, 50.4; % H, 3.3. Found: % Cl, 30.7; % C, 49.7; % H, 3.3.

EXAMPLE XIX

2,5,6-trichloro-1a,2,3,3a-tetrahydro-3a-benzylxy-1,3-methano-1H-cyclopropano(cd)naphthalene-4,7-dione

A mixture of 35 grams of 2,6,7,9-tetrachloro-1,2,3,4-tetrahydro-1,4-methanonaphthalene-5,8-dione, 8.4 grams of sodium bicarbonate, 50 milliliters of benzyl alcohol and 75 milliliters of benzene was stirred at reflux for 15 hours. The mixture was filtered and the inorganic salt was washed with methylene chloride. The filtrate was concentrated in vacuum and the residue was taken up in methylene chloride and chromatographed twice on alumina. Concentrating the eluent left a brown syrup which was steam distilled. The residue was extracted with boiling hexane and then concentrated to give an orange oil which crystallized from cold methanol to give 8 grams (21% yield) of 2,5,6-trichloro-1a,2,3,3a-tetrahydro-3a-benzylxy-1,3-methano-1H-cyclopropano(cd)naphthalene-4,7-dione, melting point 128-129° C.

Analysis.—Calculated for $C_{18}H_{13}Cl_3O_3$: % Cl, 27.8; % C, 56.4; % H, 3.4. Found: % Cl, 27.1; % C, 56.6; % H, 3.3.

15
EXAMPLE XX

2,5,6 - trichloro - 1a,2,3,3a - tetrahydro - 3a - (tetrahydrofurfuryloxy) - 1,3 - methano - 1H - cyclopropa(cd) naphthalene-4,7-dione

A mixture of 312 grams of 2,6,7,9-tetrachloro-1,2,3,4-tetrahydro-1,4-methanonaphthalene-5,8-dione, 92 grams of sodium bicarbonate and 306 grams of tetrahydrofurfuryl alcohol in 300 milliliters of benzene was heated at 90° C. for 8 hours with stirring. The reaction mixture was poured into water and extracted with ether. The ether extracts were combined and concentrated under vacuum to give a dark brown viscous liquid. This liquid was chromatographed in methylene chloride through a column of silica gel and then a column of activated alumina. The eluate was evaporated to dryness under vacuum to give 263 grams of a viscous syrup. This syrup was crystallized from methanol to give a 2,5,6-trichloro-1a, 2,3,3a-tetrahydro - 3a - (tetrahydrofurfuryloxy)-1,3-methano - 1H - cyclopropa(cd)naphthalene - 4,7-dione as a solid which melted at 50° C.

Analysis.—Calculated for $C_{16}H_{15}Cl_3O_4$: % Cl, 28.2. Found: % Cl, 28.2.

EXAMPLE XXI

2,5,6 - trichloro-1a,2,3,3a-tetrahydro-3a-hexyloxy - 1,3 - methano-1H-cyclopropa(cd)naphthalene-4,7-dione

A suspension of 15.6 grams of 2,3,6,7 - tetrachloro-1,2,3,4 - tetrahydro - 1,4 - methanonaphthalene-5,8-dione, isomer melting at 236.5-70° C., and 4.2 grams of sodium bicarbonate in 50 milliliters of n-hexyl alcohol were heated at 100-105° C. with stirring for 22 hours. The reaction mixture was filtered while hot to remove inorganic salt which gave a positive test for chloride and negative test for carbonate. The filtrate was evaporated to dryness under vacuum to leave a gummy residue. It was chromatographed in methylene chloride through a column of activated alumina. After removal of methylene chloride 2,5,6-trichloro-1a,2,3,3a-tetrahydro-3a-hexyloxy-1,3-methano-1H-cyclopropa(cd)naphthalene - 4,7 - dione, was obtained as a waxy solid: weight 7.6 grams.

Analysis.—Calculated for $C_{17}H_{18}Cl_3O_3$: % C, 54.0; % H, 5.0; % Cl, 28.2. Found: % C, 53.8; % H, 5.2; % Cl, 28.1.

EXAMPLE XXII

2,3,6,7-tetrachloro-1,2,3,4-tetrahydro-1,4-methano-naphthalene-5,8-dione

A suspension of 624 grams of 4a,6,7,8a-tetrachloro-1,4,4a,8a-tetrahydro - 1,4 - methanonaphthalene - 5,8-dione and 4 grams of iodine in 1250 milliliters of chloroform was treated in 7 hours with 265 grams of chlorine gas. The reaction mixture was heated over a steam bath to remove the excess chlorine, chilled and filtered to give 297 grams of solid, melting point 165-7°. The filtrate was evaporated to near dryness and the resulting solid was triturated with hexane, filtered and washed with ethyl acetate to give a second crop, 178 grams, melting point 164-6°. Recrystallization from ethyl acetate gave light yellow crystalline 2,3,4a,6,7,8a-hexachloro - 1,2,3,4,4a,8a-hexahydro-1,4-methanonaphthalene-5,8-dione melting at 170-1° C.

Analysis.—Calculated for $C_{11}H_6Cl_6O_2$: % Cl, 55.3; % C, 34.4; % H, 1.6. Found: % Cl, 55.2; % C, 34.5; % H, 1.6.

A suspension of 11.49 grams of 2,3,4a,6,7,8a-hexachloro - 1,2,3,4,4a,8a-hexahydro - 1,4 - methanonaphthalene-5,8-dione melting at 170-1° C. and 1.94 grams of powdered iron in 50 milliliters of absolute alcohol and 30 milliliters of benzene was refluxed for 24 hours with stirring. The reaction mixture was evaporated to dryness and the residue was extracted several times with boiling benzene. The benzene extract was evaporated to a small volume to give two crops of yellow product. The first crop weighed 3.5 grams and melted at 200-2 C.

3,291,835

16

and the second crop weighed 1.65 grams and melted at 195-7°.

EXAMPLE XXIII

2,3,6,7-tetrachloro-1,2,3,4-tetrahydro-1,4-methano-naphthalene-5,8-dione

14.2 grams of technical grade zinc dust (90% purity) was added to a suspension of 38.3 grams of 2,3,4a,6,7,8a-hexachloro-1,2,3,4,4a,8a-hexahydro-1,4-methanonaphthalene-5,8-dione in 100 milliliters of acetic acid in 12 minutes at 50-93° C. with stirring and occasional cooling. The reaction mixture was stirred for an additional 15 minutes. A solution of 8 grams of chromium trioxide (chromic acid) in 16 milliliters of water was then added to the stirred reaction mixture in 5 minutes at a temperature range of 50-73° C. The reaction temperature was then held at 80-90° C. for an additional hour. The reaction mixture was cooled, mixed with 280 milliliters of ice water, filtered and washed with 30 milliliters of methanol to give 27.1 grams of yellow product melting at 191-200° C.

EXAMPLE XXIV

In the foliage fungicide screen, three varieties of bean plants, which are hosts for four foliage fungus diseases, were employed. These hosts and pathogens are listed below. The chemicals were screened for general as well as specific test control activity and, for phytotoxicity. Diseases and hosts are shown below:

Bean hosts:

	Pathogens
<i>Phaseolus vulgaris</i> var. <i>Uromyces phaseoli</i> var. typical (rust).	Pinto -----.
<i>Phaseolus vulgaris</i> var. <i>Erysiphe polygoni</i> (powdery mildew).	Black Valentine -----.
<i>Phaseolus limensis</i> var. <i>Collectotrichum lindemuthianum</i> (anthracnose).	Fordhook 242 -----.
	<i>Phytophthora phaseoli</i> (downy mildew).

These four bean pathogens are of economic importance and represent each of four classes of fungi. *Phytophthora phaseoli* is closely allied with *Phytophthora infestans*, the important potato and tomato pathogen.

The test was carried out according to the following procedure. The test chemicals were prepared as 1% w./v. stock solutions in a solvent. The stock was diluted for spraying using a diluent consisting of distilled water plus solvent (1:1) or diluent consisting of distilled water plus two co-solvents (2:1:1). Triton X-155, at 0.005-0.10% w., was used as a wetting agent for each concentration of toxicant. All chemicals were initially tested at a single concentration of 1000 p.p.m. Disease control being shown, the chemical were retested at 1000 p.p.m., and the next lowest dilution of 500 p.p.m. The chemicals were then retested in this fashion until the minimum effective concentration was determined. Phytotoxicity assessments are expressed as the maximum "safe" concentration.

Spray applications were made using a laboratory sprayer. The bean plants were selected for use at a stage when the two primary leaves were about three-quarters expanded. To facilitate deposit, the primary leaves were oriented to a vertical position by pinning them to a small wire staff. Either the upper or lower epidermis of the leaf was exposed to the spray stream, depending on the surface to be inoculated.

With the mist-type spray and the diluent mixture which is applied, a drying interval of 1-2 hours was sufficient before inoculation with spore suspensions using a specially constructed atomizer. Inoculations with bean mildew were made by dusting conidia over treated plants in the greenhouse.

After 24 hours incubation at 19° C. and 100% humidity, the plants were removed to the controlled environment greenhouse for symptom development. Disease control and phytotoxicity assessments were made within seven

days. Of the greatest significance is the fact that compounds of the present invention are outstanding fungicides yet do not manifest significant phytotoxicity.

The following table summarizes the results of screening.

TABLE I.—FOLIAGE FUNGICIDE TESTS

	Disease Control Min. Effective Concentration (p.p.m.)				Phytotoxicity Max. "Safe" Concentration (p.p.m.)		
	P.p. ¹	E.p.	U.p.	C.I.	L	P.	B.V.

¹ P.p. = *Phytophthora phaseoli* (downy mildew of lima bean); E.p. = *Erysiphe polygoni* (bean powdery mildew); U.p. = *Uromyces phaseoli* (bean rust); C.I. = *Colletotrichum lindemuthianum* (bean anthracnose).

² L = Lima bean; P = Pinto bean; BV = Black valentine bean.

EXAMPLE XXV

In advanced greenhouse tests 2,5,6-trichloro-1a,2,3,3a-tetrahydro - 3a - ethoxy-1,3-methano-1H-cyclopropa(cd)naphthalene-4,7-dione was tested for the control of row crop diseases of major economic importance. In this test, stock solutions of the test chemical were diluted with a mixture of 2 parts distilled water, 1 part acetone, 1 part isopropyl alcohol, and 0.01% Triton X-155 (alkyl aryl polyether alcohol). The following diseases and hosts were employed for foliage fungicide assessments; potato late blight (*Phytophthora infestans*—P.i.), cucumber downy mildew (*Pseudoperonospora cubensis*—P.c.), celery late blight (*Septoria apii graveolentis*—S.a.), corn leaf blight (*Helminthosporium turicum*—H.t.), and cucumber anthracnose (*Collectotrichum lagenarium*—C.lag.). This test, the results of which are summarized in the following table, shows that 2,4,6-trichloro-1a,2,3,3a-tetrahydro - 3a - ethoxy-1,3-methano-1H-cyclopropa(cd)naphthalene-4,7-dione manifests outstanding activity as a foliage fungicide against row crop diseases. As amply shown by these tests, this test compound is particularly distinguished by its lack of phytotoxicity.

apple scab iradicant. At concentrations of the chemical ranging from 0.1 to 0.01 on a percent weight basis of the active ingredient, no disease on the test leaves was observed when spray application was made prior to inoculation. In none of the tests was phytotoxicity observed.

EXAMPLE XXVII

40 2,5,6 - trichloro - 1a,2,3,3a - tetrahydro-3a-ethoxy-1,3-methano - 1H - cyclopropa(cd)naphthalene-4,7-dione was also evaluated in the field against apple scab. Six hundredths per cent by weight of the test chemical was mixed with 2 parts distilled water, 1 part acetone, 1 part isopropyl alcohol, and 0.01% Triton X-155. When this solution was sprayed on McIntosh and Red Delicious apple trees, no leaf scab was observed on the leaves. Moreover, only 2% of the McIntosh apples scabbed whereas no scab was observed on the Red Delicious apples. When a stock solution containing 0.03% by weight of the test chemical was employed, only 2.5% leaf scab was observed on McIntosh apple leaves, and only 0.5% leaf scab was observed on Red Delicious leaves. Neither

² Figures in parenthesis represent number of tests.

EXAMPLE XXVI

In another greenhouse test, 2,5,6-trichloro-1a,2,3,3a-tetrahydro - 3a - ethoxy-1,3-methano-1H-cyclopropa(cd)naphthalene-4,7-dione was evaluated against apple scab (*Venturia inaequalis*). Stock solutions of the test chemical diluted with 2 parts distilled water, 1 part acetone, 1 part isopropyl alcohol and Triton X-155 (alkyl aryl polyether alcohol) were sprayed on leaves prior to and 24 hours after disease inoculation. Concentration of the test chemical was varied from 0.2 to 0.01 on a percent

70 75 the McIntosh nor the Red Delicious apples evidenced fruit scab at this concentration.

EXAMPLE XXVIII

A field test was also conducted employing 2,5,6-trichloro-1a,2,3,3a-tetrahydro - 3a - ethoxy - 1,3-methano-1H-cyclopropa(cd)naphthalene-4,7-dione to combat potato late blight (*Phytophthora infestans*). The test compound was employed at the rate of 0.5, 1.0 and 2.0 pounds of active ingredient per 100 gallons of spray ap-

plied at 170 gallons per acre. At all levels tested, 2,5,6-trichloro-1a,2,3,3a-tetrahydro-3a-ethoxy-1,3-methano-1H-cyclopropanaphthalene-4,7-dione was highly effective in control of blight yet did not evidence phytotoxicity. At the two-pound level, when tested under identical conditions, this compound was superior to the commercial product Dithane Z-78.

EXAMPLE XXIX

Not only are the compounds of the present invention effective fungicides when sprayed on plants but they may also be placed in the soil to combat soil-inhabiting phytopathogenic organisms. In one test showing the extraordinary effectiveness of compounds of the present invention in the soil, screening soil was sterilized by steam. Approximately 60 grams of the sterilized soil was then placed in 25 x 200 mm. test tubes and each tube separately infested with *Pythium ultimum* or *Fusarium oxysporum*. After pea and sugar beet seeds were planted at approximately one-half inch below the soil surface, the soil was drenched with a solution of the test chemical. 2,5,6-trichloro-1a,2,3,3a-tetrahydro-3a-ethoxy-1,3-methano-1H-cyclopropanaphthalene-4,7-dione melting at 172-3°C. was effective in combating both *Pythium ultimum* and *Fusarium oxysporum* when employed at a concentration of only 60 p.p.m. 2,5,6-trichloro-1a,2,3,3a-tetrahydro-3a-methoxy-1,3-methano-1H-cyclopropanaphthalene-4,7-dione was effective against these microorganisms at a concentration of 20 p.p.m.

For horticultural purposes, the active compounds of the present invention may be used alone or in combination with other fungicidal, viricidal, insecticidal or acaricidal materials, the action on which may be either internal or external, with plant nutritives, plant hormones, and the like. Wetting agents and, if necessary or desirable, stickers such as the heavy hydrocarbon oils with a minimum viscosity of 10° Engler at 50°C. can be present. The wetting agent must be non-reactive with the compounds of the present invention. Non-ionic surfactants seem preferable. If the toxic agents are employed in the form of emulsions or suspensions, for example, in water, solvents such as oils, emulsifiers, emulsion stabilizers, and the like may be added. Materials which suppress phytotoxic action may also be added if desired. For example, glucose is known to protect tomato plants against damage by certain substances having a phytotoxic effect when employed in concentrated form.

For horticultural purposes, the compounds of the present invention may be applied by means of spraying. Spraying of the plants to be treated may be performed with aqueous emulsions, solutions, or suspensions of the active agents. The spray liquid is generally applied at a rate of from about 75 to 150 gallons per acre. If spraying is effected with smaller quantities of liquid as in low volume spraying, high concentrations of the active agents should be employed. If desired, a minor amount of the order of about 0.01 to about 0.05% by weight of a wetting agent may be added to aid in forming a suspension in the aqueous medium. Any of the conventional wetting agents can be employed. Particularly suitable wetting agents are the sodium salts of a mixture of secondary heptadecyl sulfates, sold commercially under the name of "Teepol" and polyethylene glycol ethers of alkyl phenols sold under the trade name of "Triton X-100" and "Triton X-155." Preferable concentrate compositions comprising an active compound of the present invention and a suitable wetting agent are prepared, and the concentrate is then dispersed in water prior to use.

A further form in which the fungicidal compounds of the present invention may be applied for horticultural purposes consists of solutions of the active ingredient in suitable inert liquid or semi-solid diluents in which the active ingredient is present in molecularly dispersed form. The form in which the agents to be employed are applied

to the objects treated depends on the nature of the object and the purpose of the application.

Suitable inert solvents for the manufacture of liquid preparations should not be readily inflammable, as odorless as possible and without any toxic effect on humans and animals when properly used. Neither should they have a corrosive effect on the components of the preparations or the material of the storage vessel. Examples of suitable solvents are high boiling oils, e.g., oils of vegetable origin such as castor oil, etc., and lower boiling solvents with a flash point of at least 30°C., such as carbon tetrachloride, ethylene dichloride, acetylene tetrachloride, hydrogenated naphthalene, alkylated naphthalene, sorbent naphtha, etc. Mixtures of solvents may also be used. Non-aromatic petroleum oils and xylene are commonly employed.

The active compounds of the present invention may also be applied for horticultural purposes in the form of dusts utilizing as the inert vehicle such materials as tricalcium phosphate, precipitated chalk, bentonite, kaolin, kieselguhr, etc. These compounds may also be employed in the form of aerosols. For this purpose the active ingredient is dissolved or dispersed in a solvent boiling below room temperature at atmospheric pressure.

The compounds of the invention have been found to have a surprisingly low mammalian toxicity. For example, the product illustrated by Example I has been fed to rats under standardized conditions for toxicity determination at rates up to 15 grams per kilogram without observing either chronic or acute toxicological reactions. Such products are thus useful where mammalian toxicity would be a drawback, e.g., for rot- and mold-proofing materials to be brought into contact with humans, such as cloth, paper, wood, etc., and as anti-fungal agents in cosmetic preparations, lotions, and in soaps and other detergents. Indeed, their apparent low mammalian toxicity is one of their valuable attributes in all potential areas of use of the novel compounds of the invention.

The compounds of the present invention are active against a broad spectrum of microorganisms and bacteria in addition to the foliage and soil-inhabiting fungi already discussed. As a consequence of this unique activity, the compounds of the present invention may be employed in controlling microorganisms pathogenic to warm-blooded animals, such as man, livestock and domestic animals.

EXAMPLE XXX

In one series of tests showing this activity in vitro four species of bacteria were employed in a test tube dilution screen. In this test all organisms were incubated for 24 hours at 37°C. Emerson's medium was employed for all types of bacteria. The results of these tests employing endones of this invention are summarized in the following table:

60	Organism	End point in microorganism per ml. of medium (p.p.m.) for complete inhibition		
		A ¹	B ²	C ³
65	Gram-negative bacteria: <i>Pseudomonas aeruginosa</i>			<50
	Gram-positive bacteria: <i>Bacillus subtilis</i>	<2	<50	2-5
	<i>Staphylococcus aureus</i>	5	<50	1.5
	Acid fast-bacteria: <i>Mycobacterium avium</i>	10	<50	<10
	<i>Mycobacterium tuberculosis</i>	10	<50	5-10
	Fungus: <i>Fusarium oxysporum</i>			

¹ Test compound A-2,5,6-trichloro-1a,2,3,3a-tetrahydro-3a-ethoxy-1,3-methano-1H-cyclopropanaphthalene-4,7-dione. M.P. 172-3°C.

² Test compound B-2,5,6-trichloro-1a,2,3,3a-tetrahydro-3a-isopropoxy-1,3-methano-1H-cyclopropanaphthalene-4,7-dione.

³ Test compound C-2,5,6-trichloro-1a,2,3,3a-tetrahydro-3a-hexyloxy-1,3-methano-1H-cyclopropanaphthalene-4,7-dione.

EXAMPLE XXXI

When ten mice were treated with 2,5,6-trichloro-1a,2,3,3a-tetrahydro-3a-hexyloxy-1,3-methano-1H-cyclopropa(cd)naphthalene-4,7-dione at 10 milligrams for kilogram body weight and 16 hours later challenged with a virulent strain of *Listeria monocytogenes*, 80% of the mice survived. Ten untreated mice similarly challenged gave complete mortality.

Three other groups of ten mice were treated with 2,5,6-trichloro-1a,2,3,3a-tetrahydro-3a-hexyloxy-1,3-methano-1H-cyclopropa(cd)naphthalene-4,7-dione at 25 milligrams per kilogram body weight then inoculated with a highly infectious strain of *Staphylococcus aureus* 72, 96, and 120 hours, respectively, after treatment. The percentage of mice surviving the 72, 96 and 120 hour challenges were 40, 90 and 60, respectively. Three sets of untreated controls gave complete mortality when inoculated with the pathogen.

In a further test, turkeys infected with pleuropneumonia-like organism, *Mycoplasma gallisepticum* were injected with 2,5,6-trichloro-1a,2,3,3a-tetrahydro-3a-hexyloxy-1,3-methano-1H-cyclopropa(cd)naphthalene-4,7-dione at 500 and 1500 milligrams per bird. The results are summarized in the table below.

Compound	Dosage, milligrams/bird	Percent with infected sinuses	Percent with respiratory rales
2,5,6-trichloro-1a,2,3,3a-tetrahydro-3a-hexyloxy-1,3-methano-1H-cyclopropa(cd)naphthalene-4,7-dione	500	60	66
Terramycin	1,500	35	22
Untreated control	500	65	50

EXAMPLE XXXII

Compounds of the present invention have been shown to be active in controlling nematodes which infect mammals. Mice, heavily parasitized with the tapeworm, *Hymenolepis nana* and the pinworm, *Syphacia obvelata*, were given the test compounds orally at 500 milligrams per kilogram. Three days after treatment the mice were sacrificed and the intestinal tract checked for the presence of parasites. All mice tolerated the test dosage of the compounds. The following table illustrates the activity of the compounds of this invention to control intestinal nematodes of mammals.

Compound	Percent of mice cleared of nematodes after treatment	
	Tapeworms	Pinworms
2,5,6-trichloro-1a,2,3,3a-tetrahydro-3a-ethoxy-1,3-1H-cyclopropa(cd)naphthalene-4,7-dione M.P. 172°-3° C.	80	40
2,5,6-trichloro-1a,2,3,3a-tetrahydro-3a-methoxy-1,3-methano-1H-cyclopropa(cd)naphthalene-4,7-dione	100	40
2,5,6-trichloro-1a,2,3,3a-tetrahydro-3a-hexyloxy-1,3-methano-1H-cyclopropa(cd)naphthalene-4,7-dione	100	100
2,5,6-trichloro-1a,2,3,3a-tetrahydro-3a-dodecyloxy-1,3-methano-1H-cyclopropa(cd)naphthalene-4,7-dione	80	20
2,5,6-trichloro-1a,2,3,3a-tetrahydro-3a-isopropoxy-1,3-methano-1H-cyclopropa(cd)naphthalene-4,7-dione	100	100
2,5,6-trichloro-1a,2,3,3a-tetrahydro-3a-(tetrahydrofurfuryloxy)-1,3-methano-1H-cyclopropa(cd)naphthalene-4,7-dione	80	80

Thus, compounds of this invention are of value in the prophylaxis and treatment of certain diseases of warm-blooded animals, such as man, livestock and domestic animals. According to the present invention compositions suitable for treatment of animals include in addition to the active compounds of the invention pharma-

ceutical or veterinary carriers which may either be solid or liquid materials. Preparations for oral injection can be liquids or solids or any combination of these forms, such as syrups, elixirs, emulsions, powders, capsules or tablets. Preparations for administration of the active agent in unit doses can take the form of compressed powders on tablets or of a powder enclosed in a suitable capsule of absorbable material such as gelatin. The compressed powders, tablets, or capsules may also comprise suitable excipients and/or diluents such as starch, lactose, stearic acid, magnesium stearate, dextrin, polyvinyl pyrrolidine or other diluents known to the pharmaceutical formulating art.

Preparations for parenteral administration may be in the form of sterile solutions or suspensions in such liquids as water, physiological saline, benzyl alcohol, ethyl oleate, corn oil, peanut oil, Carbowax 600 (water soluble polyethylene, approximate molecular weight 600), Carbowax 400 (water soluble polyethylene, approximate molecular weight 400), glycerol monooleate, Methocil (water soluble methylcellulose) and the like, dimethyl sulfoxide, and may contain soluble or insoluble diluents and/or solid or liquid excipients.

Compositions according to this invention may be employed as feed supplements. Compounds of the present invention may be mixed with an inert carrier or diluent. An inert carrier is one that is nonreactive with respect to the compounds of this invention and may be administered with safety to the animals to be treated. The carrier may be one of the ingredients of the animal feed or may be attapulgus clay, pyrophyllite, bentonite and the like or may be of vegetable origin; corn cob meal, walnut shell flour, citrus meal, grain meal, grain hull meal or the like or may be of animal origin; bone meal, oyster shell meal, blood meal, fish meal and the like.

Compounds of this invention may be employed neat, with suitable carriers, or in combination with other medicants, vitamins, hormones, or growth stimulants.

The compounds of this invention may be mixed into the feed of animals, given in their drinking water, administered parenterally or intubated orally. As little as 0.1 milligram per kilogram of body weight may be sufficient to protect the animal or to control certain pathogenic organisms or as much as 100 milligrams per kilogram of body weight may be employed. As feed or water additives a dosage of as low as 0.5 part per million or as high as 500 parts per million of the compound may be required.

Compositions of compounds of this invention and suitable inert carriers, vehicles, or diluents may contain as little as 0.0001% of the active ingredient or as much as 100% of the active compound.

I claim as my invention:

1. 3a - substituted - 1a,2,3,3a - tetrahydro-1,3-methano-1H-cyclopropa(cd)naphthalene - 4,7 - diones of the formula:

wherein each R, independently, is a member of the group consisting of hydrogen, middle halogen, unsubstituted alkyl of from one to ten carbon atoms, alkoxy of from one to ten carbon atoms, the alkyl moiety thereof being unsubstituted; R' is a member of the group consisting of unsubstituted, mono-, and poly-(middle halogen)- substituted alkyl of from one to ten carbon atoms, allyl, benzyl, methoxyethyl, hydroxyethyl, dihydroxypropyl, tetrahydrofurfuryl, tetrahydropyranyl and 2,2-dimethyl-1,3-dioxolan-4-ylmethyl.

2. Polyhalo - 1a,2,3,3a - tetrahydro - 3a - alkoxy - 1,3-

23

methano - 1H - cyclopropa(cd)naphthalene-4,7-diones of the formula:

wherein R is middle halogen and R' is alkyl of 1 to 10 carbon atoms.

3. Diones defined in claim 2 wherein R represents chlorine.

4. 2,5,6-trichloro-1a,2,3,3a-tetrahydro-3a-ethoxy-1,3-methano-1H-cyclopropa(cd)naphthalene-4,7-dione.

5. 2,5,6-trichloro-1a,2,3,3a-tetrahydro-3a-methoxy-1,3-methano-1H-cyclopropa(cd)naphthalene-4,7-dione.

6. 2,5,6-trichloro-1a,2,3,3a-tetrahydro-3a-propoxy-1,3-methano-1H-cyclopropa(cd)naphthalene-4,7-dione.

7. 2,5,6-trichloro-1a,2,3,3a-tetrahydro-3a-hexyloxy-1,3-methano-1H-cyclopropa(cd)naphthalene-4,7-dione.

8. 2,5,6-trichloro-1a,2,3,3a-tetrahydro-3a-chloroethoxy-1,3-methano-1H-cyclopropa(cd)naphthalene-4,7-dione.

24

9. A dione defined by the formula:

wherein R and R' are alkyl of 1 to 10 carbon atoms.
